UNITED STATES PATENT OFFICE.

WILLIAM WESLEY HICKS, OF SAN FRANCISCO, CALIFORNIA.

ELECTRIC HEATING CORE.

1,421,084.

Specification of Letters Patent. Patented June 27, 1922.

Application filed August 16, 1920. Serial No. 403,942.

To all whom it may concern:

Be it known that I, WILLIAM WESLEY HICKS, a citizen of the United States, residing in the city and county of San Francisco and State of California, have invented a new and useful Improvement in an Electric Heating Core, of which the following is a specification.

This invention relates to improvements 10 in cores for electric heaters and the like whereon heating coils may be non-inductively wound and is a continuation of my co-pending application, Serial No. 269,865, filed January 6th, 1919, reference to which is 15 hereby made.

The primary object of my invention is to provide an improved heating core adapted for non-inductive winding of heating coils.

Another object is to provide a heating 20 core of the type described which may be placed in close thermal contact with a fluid container to be heated.

A further object is to provide an improved 25 heating core arranged to permit non-inductive winding of a plurality of independent circuits.

A still further object is to provide a core 30 of refractory dielectric material arranged to insulate the heating coils from each other and from adjacent members.

A still further object is to provide a heating element of the type described for use 35 in heaters for either liquid or gaseous products.

I accomplish these and other objects by means of the novel device disclosed in the drawings forming a part of the present specifications wherein like characters of reference are used to designate similar parts throughout said specification and drawings, and in which:

Fig. 1 is a broken vertical section of a water heater element applied thereto.

Fig. 2 is a horizontal section taken on the line 2—2 of Fig. 1 in the direction indicated.

Fig. 3 is a broken front elevation of an air heater disclosing my improved non-inductively wound cores.

Fig. 4 is a section taken on the line 4—4 of Fig. 3 in the direction indicated.

Fig. 5 is a side elevation of an immersion heater, a portion being broken away and

shown in section to disclose my improved 55 core as applied therein.

Fig. 6 is a side elevation of my core disclosing the non-inductive winding.

Fig. 7 is a bottom view of the core disclosed in Fig. 6 disclosing a continuous 60 winding for a single circuit.

Fig. 8 is a view similar to Fig. 7 disclosing the terminals for multiple circuit winding.

Referring to the drawings the numeral 1 65 is used to designate in general a core of any suitable refractory dielectric material such as fire clay, in the form of a hollow cylinder open at both ends. The core 1 may be formed in semi-cylindrical halves 1^a to simplify manufacture and facilitate the application to of the core to a container. A plurality of ribs 2 are spirally disposed upon the outer surface of the core 1 to form a plurality of parallel spiral grooves 3 in 75 the nature of a mutiple thread screw of any desired pitch.

Resistance coils 4 of any suitable character are non-inductively wound upon the core 1. The non-inductive winding is obtained by advancing the coil 4 along one of the grooves 3 from a feed terminal 6, and returning the coil 4 along the next adjacent groove 3, the two portions of the coil 4 forming advance spirals 8 and return 80 spirals 9 connected by a loop 10 passing around the end of the intervening rib 2 or through apertures 5 provided in the ends thereof. The return spiral 9 of the coil 4 may be looped about the lower end of the 90 next rib 2 as at 11, and advanced and returned as before to give a continuous circuit as shown in Fig. 7, or the end may be made a return terminal 7, and other coils 4 independently connected to the source of 95 electrical energy wound in similar manner in the remaining pairs of grooves 3 as shown in Fig. 8. For the purpose of illustration I have disclosed a single resistance coil wound upon my improved core, the continuation of the coil 4 through the remaining grooves 3 for a single circuit of greater length or the application of independent coils 4 in succeeding pairs of grooves 3 for

multiple circuit winding being only a continuation or a repetition of the method above described. In either case the feed terminals 6 and the return terminals 7 are 100 105

located at the same end of the core 1. As each advancing spiral 8 of the coil 4 is paralleled by a similar return spiral 9 carrying current in the opposite direction, it is 5 obvious that the current induced by either spiral will be neutralized by that current induced by the opposing spiral, and the flow of induced current thereby reduced to zero. In multiple winding each advancing spiral 10 8 is paralleled by a return spiral 9 and the induced current in either direction will be neutralized by an equal current induced in the opposite direction. Since there can be 15 no flow of induced current, my improved core wound in the manner I have described results in a non-inductive heating element adapted for use in air or water heaters or other heating devices of a similar nature.

In Figs. 1 and 2 I have disclosed my 20 novel heating element as applied in a circulation water heater in which the core 1 with a resistance coil 4 wound as above described is positioned in close thermal contact with a heating pipe 11 connected with 25 a boiler or the like, not shown, in the usual manner. Bus-bars 12 provided with connections 14 for feed terminals 6 and return terminals 7 are suitably secured adjacent the lower end of the core 1 to deliver current 30 from a source of electrical energy, not shown, to the resistance coils 4. Only a single advance spiral 8 with its return spiral 9 having terminals 6 and 7 is disclosed to illustrate the manner in which additional 35 coils 4 may be applied in the remaining pairs of grooves 3 or the same coil 4 may be continued throughout as desired. Coils lying in adjacent grooves are insulated from each other by the intervening rib 2.

40 As the pipe 11 is heated by contact with the core 1, the water therein is heated and circulation through the supply pipe 16 and delivery pipe 17 caused in the usual manner. Heat radiated from the outer surface 45 of the core 1 and coil 4 is utilized by enclosing the heating element in a double walled jacket 18 connected to the supply pipe 16 by a connection 19 at the bottom thereof, and opening at the top into the delivery 50 tube as at 21. Circulation is accomplished through the jacket in the same manner as in the heating tube, the heating and the resulting circulation being necessarily slower.

55 In Figs. 3 and 4 I have disclosed an air heater equipped with my improved heating elements. In this case the cores 1 are provided with flanges 26 arranged to rest on a floor 27 provided in a housing 28 open 60 in the front thereof to permit the escape of heated air and direct radiation of heat from the coils 4 and cores 1. The floor 27 is provided with apertures 29, the hollow cores 1 being arranged to register therewith. Circulation of air through the cores

1 is caused in a manner similar to the action of water in a water heater, the air being heated within the core 1 and displaced by cooler air admitted from the bottom. Connections 31 are provided for the 70 terminals 6 and 7 and a source of electrical energy, not shown, is connected thereto through bus bars 32. One, two or three sets of the advance spirals 8 and return spirals 9 may be provided in single or 75 multiple circuit as desired on the core disclosed. The bus bars 32 are spaced on opposite sides of the apertures 29 to permit ready circulation of the air.

Fig. 5 illustrates my improved heating 8 element as applied to an immersion heater. In this case the core 1 is enclosed in a housing 36 closed at one end thereof and provided at the other end with a suitable cap 37 adapted to receive an insulating bushing 38 arranged to admit wires 39 conducting current to the coils 4 of the heating element. The core 1 and resistance coils 4 are entirely enclosed within the housing 1 and a filling of insulating materials 41 adapted 9 to conduct heat is applied between the core 1 and the housing 36 for obtaining a close thermal contact therewith, heat being imparted through the outer housing wall 36 to the element in which the heater is immersed.

I have disclosed a core provided with six spiral ribs 2 to provide grooves 3 for retaining six spiral resistance coils. However, I do not wish to limit myself to this 1 specific construction as any number of spirals may be provided to suit different requirements, the non-inductive principle being unaltered by the number of parallel coils employed. In like manner the pitch 1 and character of the coils 4 may be varied to suit varied requirements. The drawings disclose the manner in which my improved heating element may be applied to different types of electric heaters, the core and winding also being equally adaptable to any other type of heating device wherein a resistance wound core is employed.

Having thus described my invention what I claim as new and desire to secure by Letters Patent is:

1. In an electric heater, a heating element comprising a refractory core; and a plurality of multiple circuit resistance coils separately wound in parallel spirals thereon 1 to prevent induction, both terminals of all coils being independently connected at the same end of said core.

2. In an electric heater, a heating element comprising a refractory core; ribs 1 spirally disposed upon the outer surface of said core to form grooves thereon; multiple circuit resistance coils separately wound upon the core, said coils being guided by the grooves into parallel spirals to prevent in- 1

duction, each circuit coil advancing and returning in adjacent grooves and being insulated by the intervening rib, the terminals of said coils being independently connected 5 at the same end of the core.

3. In an electric heater, a heating element comprising a hollow refractory core formed in semi-cylindrical sections arranged to be removably assembled in close thermal contact around a surface to be heated; ribs 10 spirally disposed upon the outer surface of

said core to form grooves thereon; resistance coils separately wound in parallel spirals arranged to advance and return in adjacent grooves and insulated by the intervening rib to prevent induction, the terminals of said coils being independently connected at the same end of said core. 15

In witness whereof I hereunto set my signature.

W. WESLEY HICKS.
